UNITED STATES PATENT OFFICE.

DAVIS B. SPHALER AND BENJAMIN F. BRYAN, OF TAFT, FLORIDA.

TURPENTINE-SEPARATOR.

974,717.

Specification of Letters Patent.

Patented Nov. 1, 1910.

Application filed March 2, 1910. Serial No. 546,780.

To all whom it may concern:

Be it known that we, DAVIS B. SPHALER and BENJAMIN F. BRYAN, citizens of the United States, and residents of Taft, in the 5 county of Orange and State of Florida, have invented certain new and useful Improvements in Turpentine-Separators, of which the following is a specification.

This invention is an improvement in tur- 10 pentine separators designed for use in separating the turpentine as it is delivered from a still from the water, sediment and other impurities and permit the delivery of the turpentine to a cask or other receptacle 15 freed from the said impurities; and the invention consists in certain novel constructions and combinations of parts as will be hereinafter described and claimed.

In the drawings Figure 1 is a detail per- 20 spective view of the separator, Fig. 2 is a vertical longitudinal section thereof, a portion of the still and of the barrel and the water receptacle being shown in dotted lines, and Fig. 3 is a detail vertical section show- 25 ing the overflow from the intermediate chamber.

The still A has a discharge at B which de- 30 liveres into an inlet compartment C of the separator, said compartment C being along- 35 side an intermediate compartment D and separated therefrom by a partition E which is perforated to permit the circulation of the liquid between the compartments C and D. This partition E operates mechanically 40 to separate certain impurities, such for instance as chips, pieces of bark and the like and also operates to quiet the ebullition and turbulence of the liquid discharged from the still so that the liquid within the compart- 45 ment D will be comparatively quiet so the turpentine and water can separate and the water drop to the bottom where it may be discharged through an outlet F which may, as shown, be in the form of a faucet while 50 the turpentine may be discharged through an opening G near the top of the outlet compartment D into the compartment H, whence it may be drawn through the outlet I into the cask or other receptacle J as shown in Figs. 1 and 2 of the drawings.

As shown in Fig. 2, the outlet I from the

compartment H is located at the bottom thereof and such bottom slopes laterally in both directions toward the outlet as shown in Figs. 1 and 3 of the drawing. We pro- 55 vide an overflow at K from the intermediate compartment or chamber D, such overflow being in the form of a tube open at its upper end a short distance below the top of the compartment D and having at its lower end 60 a discharge pipe K' which may deliver to a barrel or other suitable receptacle. The faucet I is arranged to deliver at I' into the barrel J and has a lever I² for operating its valve through the aid of a float I³ arranged 65 in the barrel and having a rod I⁵ extending up through the bung hole and connected with the lever I² so that when the barrel J fills the float I³ will be lifted and will tilt the lever I² to close the faucet I. The dis- 70 charge pipe I' has a valve at I⁵ which may be manually controlled.

We claim:

1. The separator herein described comprising an inlet compartment, an outlet compartment and an intermediate compartment between the inlet and outlet compartments, an overflow pipe in the intermediate compartment, a perforated partition between the inlet compartment and the intermediate 75 compartment, an outlet from the upper end of the intermediate compartment to the outlet compartment, an outlet at the lower end of the intermediate compartment, a discharge faucet at the lower end of the outlet 80 compartment and having a projecting valve operating lever and a float for operating the same, all substantially as and for the purposes set forth.

2. A turpentine separator comprising a 90 pan like body open at the top and divided into three compartments with partitions di- 95 viding the inlet, intermediate and outlet compartments, the inlet and intermediate compartments occupying one end of the pan 95 and the outlet compartment the other end of the pan, the latter having a discharge at its lower end and a bottom inclining down- 100 wardly toward such discharge, the partition between the inlet and intermediate compartments being perforated and a discharge opening being provided near the top of the

partition between the intermediate and outlet compartments, the intermediate compartment being provided with a discharge at its lower end and also having an overflow tube 5 opening at its upper end within the intermediate compartment below the top of such compartment and having at its lower end a

discharge pipe, all substantially as and for the purposes set forth.

DAVIS B. SPHALER.
BENJAMIN F. BRYAN.
